UNITED STATES PATENT OFFICE.

AUGUSTUS L. HAHL, OF CHICAGO, ILLINOIS.

SECONDARY-CLOCK MOVEMENT.

1,271,704.

Specification of Letters Patent.

Patented July 9, 1918.

Application filed October 29, 1912. Serial No. 728,339.

To all whom it may concern:

Be it known that I, AUGUSTUS L. HAHL, a citizen of the United States, residing at Chicago, in the county of Cook and State of Illinois, have invented certain new and useful Improvements in Secondary-Clock Movements, of which the following is a specification.

My invention relates to secondary clock mechanism which is intended for use in time systems in which a master clock controls said secondary clocks by an air conduit or other connecting means leading from said master clock to said secondary clocks.

Among the principal objects of my invention are to provide a protected actuating diaphragm in the secondary clock; to provide means for preventing stretching, and consequent stiffening, of said diaphragm, and other means by which all damage to the diaphragm is prevented; to provide a plunger plate which is actuated by said diaphragm without being attached thereto, and which is freely guided and linked to the diaphragm casing; to provide convenient devices whereby the diaphragm may be quickly removed and renewed without the necessity of reaching into the mechanism; to provide means for positive adjustment of the plunger plate with relation to the clock mechanism without the possibility of accidental shifting; to provide an escapement mechanism in which both actuating pawls have inherent equal movements to insure uniform margin of movement with minimum movement of the diaphragm; to insure accurate positioning of the hands; and other features which will be rendered apparent in the following specification, when taken in connection with the accompanying drawings, in which—

Figure 1 is a front elevation, partly in section, of my improved secondary clock mechanism on an enlarged scale.

Fig. 2 is a horizontal section thereof, taken on the line 2—2 of Fig. 1.

Fig. 3 is a side elevation of the clock mechanism.

Fig. 4 is a detail plan view of one of the levers, showing its connections with the diaphragm.

Fig. 5 is a perspective view of a wedge device which opens the connecting link.

Fig. 6 is a perspective view of the connecting link.

Fig. 7 is a perspective view of the pawl-carrying link.

Fig. 7^a is a perspective view of a fragment of the link shown in Fig. 7.

Fig. 8 is a perspective view of the flexible adjusting arm for the connecting link.

Fig. 9 is a perspective view of a portion of the lower lever; and

Fig. 10 is a sectional view of said lever, taken on the line 10—10 of Fig. 1.

Referring more particularly to Fig. 1, it will be seen that I employ a flexible diaphragm 15 for receiving the air pressure from the conduit leading from the master clock, and that I impart the motion to the clock mechanism by means of the link 16. This link is provided with suitable devices at its ends for receiving the pressure of the diaphragm and also for imparting said movement to the clock mechanism, all of which will be more fully described below.

The link 16 imparts its movement to the lever 17, which, in turn, imparts the movement to the pawl carrier 18, which in general occupies a vertical position in the mechanism. The lever 17 is pivotally mounted in the frame. The pawls 19 and 20 thus carried actuate a toothed wheel 22, commonly called an escapement wheel. The upper end of the pawl carrier 18 is pivotally connected with the lever 21, which is mounted in the main frame in a similar manner to the lever 17.

This toothed wheel is fixed to a shaft 28, rotatably mounted in the frame. This shaft through the usual transmission gearing 23 carries and moves the hour and minute hands. The pawl carrier 18 is provided with a horizontally extending arm 29, to which is pivotally attached the pawl 19 by means of a pin 30. This pawl is provided with a weighted end 31, which maintains the upper end of said pawl in engagement with the teeth of the wheel. Said pawl is also provided with a lug or heel 31^a, which prevents the upper end of said pawl engaging the teeth too deeply.

The pawl carrier 18 is also provided with an arm 32, which carries the other pawl 20 in operative relation to the wheel 22 on the opposite side to that of the pawl 19. The 5 pawl 20 is pivotally attached to said arm 32 by means of a pin 33. The weighted end 34 of said pawl causes the lower end thereof to maintain engagement with the wheel 22, and the outer end 34^a of the arm 32 serves as a 10 stop for said pawl to prevent too deep engagement.

The lever 17 is provided with a wedge-shaped end produced by the converging faces 36 and 37, which enters the spaces between the teeth and serves as a positioning means for said teeth at the end of each upward stroke of the lever. The vertical face 36^a, adjoining the face 36, serves as a positive stop for the teeth of the wheel, thereby 15 properly limiting the motion thereof.

The lever 21 is provided with a similar wedge-shaped end 35^a, the outer face 36^b in this case serving as a stop. The lever 17 is pivotally mounted in the main frame by 20 means of the pin or axle 38, and is provided with a counterbalancing arm 39. The lever 21 is provided with a similar pin or axle 38^a and counterbalancing arm 39^a.

The link 16 is connected with the lever 17 30 by indirect means for the purposes of adjustment, which consists of a flexible arm 40, riveted, as at 41, or integral with said lever. At the other end of this flexible arm is an eye 42, through which a pin may be 35 inserted, said pin also passing through holes in the upper end of the link 16. A thumb screw 43, carried by a lug 44 on said lever, provides a convenient means for adjusting the precise position of the arm 40 with respect to the body of the lever 17. By this 40 means the relation between the diaphragm and the lever 17 may be very conveniently adjusted.

The link 16 comprises two side members 45 and 46, which are preferably integrally connected at their upper ends, thereby forming an elastic device which may be very conveniently sprung into connection with the part which is actuated by the diaphragm. 50 The lower end of this link is provided with inwardly turned ends 47 and 48, in which circular notches are cut, and which thereby form means for engaging the neck 51 of said part. The socket thus formed in the lower 55 end of the link for engaging the neck is shown at 49. Inclined faces 50 and 50^a leading to said socket serve to guide the link into operative connection with said neck when the link is being sprung into place. A 60 tongue 60, bent inwardly, prevents the link being pressed too far by engaging with the head 52 immediately above said neck.

The wedging device 54 is placed between the side members 45 and 46 and is pivotally 65 mounted at 57 upon the same pin previously

mentioned which is inserted in the eye 42 of the arm 40. This wedging device is provided with two outwardly projecting wedges 55 and 56, which press the side walls of the link 16 outwardly when said device is 70 pushed between them. This action causes the two halves of the socket 49 to become sufficiently disengaged from the neck 51 to permit the link 16 to be swung out of connection therewith. A lug 59 prevents the 75 wedging device being swung too far away from the link, into a position which cannot be readily reached by the operator.

The head 52 is integrally connected by the neck 51 with the hub 53, to which a circular plunger plate 65 is concentrically attached. This plate is adapted to lie loosely upon the upper surface of the diaphragm and will be actuated thereby without being positively connected therewith by fastening devices or other means. The diaphragm 15 is thereby retained in its integral and undamaged condition. Between said plate and the diaphragm 15 I preferably insert a circular sheet of flexible material 66 for the purpose of preventing adhesion of the diaphragm to the plate. The grooves or depressions 67^a, 68^a in the inner faces of the diaphragm case prevent entire exclusion of the air and therefore prevent adhesion of the surfaces.

The hub 53 is guided in a vertical direction and held in a concentric position by the radial links 61, 62 and 63, which are pivotally attached to the diaphragm casing 69 at their outer ends and to the hub 53 at 100 their inner ends. The main body 68 of the diaphragm casing is given a dished or concave form to snugly fit the diaphragm when the latter is in its lowermost position. The outer edges of the casing are turned upwardly, as shown at 69^a, to closely confine the outer edge of the diaphragm and to receive the upper portion 67 of the casing. This upper portion is preferably a thin 105 plate, circular in form, with a large aperture in the center. The upper portion 67 is held in position in close contact with the outer edge portion of the diaphragm by spring clips 71, which engage the main body of the casing at one end and the upper surface of 110 the upper portion 67 at the other end. These spring clips press the upper portion 67 snugly into position upon the diaphragm, and thereby lock it in position without causing any injurious rubbing or other distortion thereof.

The hollow plug 72 is riveted in an aperture in the diaphragm casing. This plug is threaded at its lower end to screw into the socket 76 fastened to the frame 75. A 125 large disk 74, projecting slightly beyond the outer circumference of the casing and provided with lugs 74^a, provides convenient means for manipulating the entire diaphragm structure, when it is desired to re- 130

move the casing and renew the diaphragm. The plug 72 is provided with a polygonal portion 73 to which the disk 74 is fitted. It will be seen that by turning the disk 74 the 5 casing can be disengaged from the frame.

The diaphragm may be removed from the casing by first removing the spring clips 71. The upper portion 67 of the casing may then be removed. Previously to this, it is necessary to disconnect the link 16 from the neck 51, thereby permitting the diaphragm plate 65 to be lifted. The outer ends of the links 61, 62 and 63 may be disconnected from the casing at 64.

15 As shown in Fig. 1, the plunger plate 65 has a diameter slightly greater than the aperture 70 in the upper casing portion 67. This upper portion thereby serves as a stop for the upward movement of the plunger plate. In order to permit the insertion of 20 the plate through said upper portion, I provide notches 67^a and 67^b, which have a radius slightly greater than that of the aperture. The plunger plate may be passed through 25 these notches in a slightly inclined position, after which it is moved into a concentric position, one side being finally disposed below the lug 67.

In operation, it will be clearly seen that an 30 impulse of air in the conduit leading to the sockets 72 will cause the diaphragm to be pressed upwardly and that said diaphragm will thereby impart a pressure to the plunger plate 65. The links 61, 62 and 63 35 will guide said plate in a vertical direction and maintain its concentric position, and by means of the hub 53 and the inwardly turned ends 47 and 48 of the link 16 said pressure will be transmitted to said link. 40 This link, by means of the pin 42 and the arm 40, will transmit the upward motion to the lever 17, which, in turn, will impart the upward motion to the pawl carrier 18. By means of the pawl 19 a rotary movement 45 will be imparted to the toothed wheel.

When the pressure in the conduit has been removed, the weight of the movable parts of the mechanism will cause a downward movement of the diaphragm and the plate 65. 50 The pawl carrier 18 will move downwardly and the pawl 20 will engage the teeth of the wheel and cause a further rotary movement thereof. The wedge-shaped ends 35 and 35^a will enter the spaces between the teeth 55 and finally cause a precise positioning of the wheel 22 and thereby an accurate positioning of the clock hands. Any tendency of the clock hands to move beyond their normal position, due to their momentum, will be 60 corrected by said wedge-shaped ends.

The operator may very conveniently disconnect the link 16 from the plunger plate by simply pushing the wedging device to the right, when the small wedges 55 and 56 65 will spread the sides of the link 16, after

which said link may be swung to one side and out of the way.

It will be seen that I have provided a very convenient and compact diaphragm structure which may be packed and shipped 70 without in any way damaging it and which may be inserted in or removed from the clock mechanism with the utmost facility. It will be seen that all assembling work on the diaphragm structure may be done in the 75 factory, thereby saving outside work. The adjustment of the stroke may also be effected with great precision and with the utmost convenience, without risk of accidental change of adjustment.

80 While I have described more or less precisely the details of construction, I do not wish to be understood as limiting myself thereto, as I contemplate changes in form and the proportions of parts and the substitution of equivalents as circumstances may suggest or render expedient without departing from the spirit of my invention.

I claim:

1. In a secondary clock movement, an escapement wheel, pawls disposed in substantially diametrically opposite operative relation to said wheel, a single pawl carrier having relatively immovable fulcrums thereon for said pawls arranged to impart equal motions to said pawls upon movement of said pawl carrier, said pawls being arranged to act alternately in driving said wheel.

90 1. In a secondary clock movement, an escapement wheel, pawls disposed in operative relation to said wheel, a single pawl carrier having relatively immovable fulcrums for said pawls arranged to impart equal motions to said pawls upon movement of said pawl carrier, said pawls being arranged to drive said wheel alternately and positioning stops for said wheel, said stops being independent of said pawls.

100 2. In a secondary clock movement, an escapement wheel, pawls disposed in operative relation to said wheel, a single pawl carrier having relatively immovable fulcrums for said pawls arranged to impart equal motions to said pawls upon movement of said pawl carrier, said pawls being arranged to drive said wheel alternately and positioning stops for said wheel, said stops being independent of said pawls.

110 3. In a secondary clock movement, an escapement wheel, a pawl disposed in operative relation to said wheel, a pawl carrier adapted upon movement thereof to actuate said pawl to drive said wheel, a motor, a link operatively connected to said pawl carrier and detachably connected to said motor, and means coöperating with said link for detaching the same from said motor.

115 4. In a secondary clock movement, an escapement wheel, a pawl disposed in operative relation to said wheel, a pawl carrier adapted upon movement thereof to actuate said pawl to drive said wheel, a motor, a link operatively connected to said pawl carrier and detachably connected to said motor, and means permanently associated with said link for detaching the same from said motor.

120 5. In a secondary clock movement, an escapement wheel, a motor, pawls disposed in operative relation to said wheel, a bodily movable pawl carrier connected with and ac-

- 5 tuated by said motor, and means comprising a flexible member for adjusting said carrier with relation to said motor.
6. In a secondary clock movement, an es-
5 capement wheel, a motor, pawls actuated by said motor, a pawl carrier, and a link connecting said motor and carrier composed of flexible arms having ends adapted to engage the movable part of said motor.
- 10 7. In a secondary clock movement, an es-
capement wheel, a motor, pawls actuated by said motor, a pawl carrier, a link connect-
ing said motor and carrier composed of
15 flexible arms having ends adapted to engage the movable part of said motor, and means associated with said link for detaching said flexible arms from said motor.
8. In a secondary clock movement, an es-
capement wheel, pawls disposed in opera-
20 tive relation to said wheel, a single sheet
diaphragm, a casing for said diaphragm, re-
silient means for holding the peripheral por-
tion of said diaphragm in air tight engage-
25 ment with said casing, a movable member
unattached to said diaphragm for receiving
motion therefrom, and means for trans-
mitting said motion from said movable member
to said pawls.
9. In a secondary clock movement, an es-
capement wheel, pawls disposed in opera-
30 tive relation to said wheel, a diaphragm op-
eratively connected with said pawls, an open
casing for said diaphragm, a movable plate
for receiving motion from said diaphragm,
35 and means to separate said plate and said
diaphragm, said movable plate coöperating
with a portion of said casing to limit the ex-
pansion of said diaphragm to prevent
stretching thereof.
- 40 10. In a secondary clock movement, an es-
capement wheel, a pawl disposed in opera-
tive relation to said wheel, a diaphragm, an open
casing for said diaphragm, a movable plate
for receiving motion from said dia-
45 phragm, means for imparting said motion
to said pawl, and guide members pivotally
connected to said casing and operatively
connected to said movable plate for guiding
the movement of the latter.
- 50 11. In a secondary clock movement, an es-
capement wheel, pawls disposed in operative
relation to said wheel, a diaphragm, an open
casing for said diaphragm, a movable plate
for receiving motion from said diaphragm,
55 and means for imparting said motion to said
pawls, said movable plate coöperating with
a portion of said casing to limit the ex-
pansion of said diaphragm to prevent stretching
thereof, said movable plate being removably
60 confined within said casing and removable
therefrom without dismantling said casing.
12. In a secondary clock movement, an es-
capement wheel, pawls disposed in operative
relation to said wheel, a single inflexible
- 65 pawl carrier for both said pawls, a pivoted mounted lever pivoted to said pawl carrier to guide the same, and a movable member associated with said lever for imparting movement thereto.
13. In a secondary time movement, a sin-
gle sheet diaphragm, means actuated by said diaphragm, a movable member unat-
tached to said diaphragm for receiving motion therefrom, and means detachably swiv-
eled to said movable member and pivotally connected to said first named means.
14. In a secondary time movement, a sin-
gle sheet diaphragm, means actuated by said diaphragm, a casing for said diaphragm, re-
silient means for holding the peripheral por-
tion of said diaphragm in air tight engage-
80 ment with said casing, and means for trans-
mitting motion from said diaphragm to said first named means.
15. In a secondary clock movement, an es-
capement wheel, a pair of pawls disposed
in operative relation to said wheel, a single
pawl carrier having relatively immovable
fulcrums thereon for said pawls, pivoted
links connected to said pawl carrier for
guiding the same in motion of translation,
and means for imparting said motion to
said pawl carrier, said parts being arranged
to give equal movement to said pawls upon
movement of said pawl carrier.
- 95 16. In a secondary clock movement, an es-
capement wheel, a pair of pawls disposed
in operative relation to said wheel, a single
pawl carrier having relatively immovable
fulcrums thereon for said pawls, pivoted
links connected to said pawl carrier for
guiding the same in motion of translation,
positioning lugs for said escapement wheel
carried by said pivoted links, and means for
imparting said motion to said pawl carrier,
100 said parts being arranged to give equal
movement to said parts upon movement of
said pawl carrier.
17. In a secondary clock movement, an es-
capement wheel, a pair of pawls disposed
in operative relation to said wheel, a single
pawl carrier having relatively immovable
fulcrums thereon for said pawl, pivoted
levers connected to said pawl carrier, said
levers being weighted at the ends thereof
opposite said pawl carrier, a motor, and
means for connecting said motor to one of
said levers whereby the operation of said
motor will operate to reciprocate said pawl
carrier and impart equal motions to said
115 pawls.
18. In a secondary clock movement, an es-
capement wheel, a pair of pawls disposed
in operative relation to said wheel, a single
pawl carrier having relatively immovable
fulcrums thereon for said pawls, pivoted
levers connected to said pawl carrier, said
levers being weighted at the ends thereof

opposite said pawl carrier, a motor, and means for connecting said motor to one of said levers whereby the operation of said motor will operate to reciprocate said pawl carrier and impart equal motions to said pawls, said connecting means being adjustably connected to said lever for regulating the movement of said pawl carrier.

19. In a secondary clock movement, an escapement wheel, pawls disposed in operative relation to said wheel, a single pawl carrier for both of said pawls, and means for imparting a parallelogram movement to said carrier, whereby equal movements are imparted to said pawls.

20. In a secondary clock movement, an escapement wheel, pawls disposed in operative relation to said wheel, a single pawl carrier for both of said pawls, means for imparting a parallelogram movement to said carrier, whereby equal movements are imparted to said pawls, and positioning lugs

actuated with said carrier for engaging said escapement wheel.

21. In a secondary clock movement, an escapement wheel, a pawl disposed in operative relation to said wheel, a single sheet diaphragm, a movable member of lesser area than said diaphragm for receiving motion therefrom, said member being unattached to said diaphragm, means for transmitting said motion from said movable member to said pawl, and link members relatively fixed at one end and operatively connected to said movable member at their other ends for guiding the latter in a straight line.

In testimony whereof I have subscribed my name.

AUGUSTUS L. HAHL.
